UNITED STATES PATENT OFFICE.

HENRY C. STOLL, OF NEW YORK, N. Y.

INTERNAL-COMBUSTION ENGINE.

1,361,114.

Specification of Letters Patent.

Patented Dec. 7, 1920.

Application filed September 18, 1919. Serial No. 324,301.

To all whom it may concern:

Be it known that I, HENRY C. STOLL, a citizen of the United States, and resident of the city, county, and State of New York, have invented certain new and useful Improvements in Internal-Combustion Engines, of which the following is a specification.

The objects of this invention are to improve and to increase the efficiency of engines of the type referred to, particularly as regards the valve mechanism.

It is highly desirable in engines of the character referred to that the valves be fully opened quickly; be held open as long as practicable and then be quickly closed.

In my invention I have attained these results through the employment of engine driven crank mechanism, involving a pair of cranks for operating each valve and timed and so connected with the valve as to produce the quick, full opening and quick closing referred to.

The construction and operation will be understood more fully by reference to the accompanying drawings wherein I have illustrated the invention embodied in several different and practical forms.

Figure 1 in said drawing is a vertical sectional view of the engine taken on a plane or planes passing through the engine piston and the exhaust valve.

Fig. 2 is a horizontal plan view of the engine cylinder, taken on substantially the plane of line 2—2 of Fig. 1.

Figs. 3, 4, 5, and 6 are diagrammatic views illustrating the "intake," "compression," "power" and "exhaust" strokes of the engine.

Figs. 7 and 8 are broken part sectional views of modified forms of the invention.

10 designates the cylinder of the engine, operating within which is the piston 11 connected with a suitable crank shaft 12, as by the medium of a connecting rod 13.

In the engine herein disclosed the valves are of the "piston" type, the exhaust valve being indicated at 14 and the intake valve at 15, said valves operating in the cylindrical valve chambers 16 and 17 provided therefor in the engine casting. These

valves are suitably ported, as indicated at 17 in Fig. 1, said ports opening into a suitable outlet passage 18, in the case of the exhaust valve and into a suitable inlet 19 in the case of the intake valve.

The operating cranks for the exhaust valve are designated 20 and 21, said cranks being carried by the crank shafts indicated at 22 and 23 and connected with the valve, in the first form disclosed, through the medium of connecting rods 24, 25 pivotally engaged with the opposite ends of a rocker 26, which is pivotally connected at 27 to a rod 28, which is shown as directly connected with the valve.

These valve cranks are driven from the engine crank shaft through suitable gearing, such as a silent chain 29 and this gearing is such that one crank (20) will be turned at engine speed while the other crank (21) will be turned at half engine speed. This may be accomplished by making the sprocket or gear 30 on the first valve crank shaft of the same size or number of teeth as the sprocket or gear 31 on the main crank shaft and the sprocket or gear 32 on the second valve crank shaft of twice the size or number of teeth.

Also in the construction disclosed the full time crank 20 is of shorter stroke than the half time crank 21. All of this crank mechanism is shown as disposed within the crank case of the engine where it will be fully lubricated at all times. The valve lift rods indicated at 28 may be suitably guided as by means of guides indicated at 33 and 34.

The inlet valve is operated by cranks 35 and 36 on the same shafts with the cranks 20 and 21 and as shown in this instance, of the same stroke. These inlet cranks are however, offset from the exhaust cranks, the first a matter of 180° and the second a matter of 90°. The inlet cranks are connected with the inlet valve through the medium of the connecting rods 37 and 38 and rocker 39, which latter is connected with the inlet valve push rod 40.

In Fig. 1 the parts are indicated in the position with the piston halfway up on its exhaust stroke. At this time both the ex-

haust valve cranks are at the bottom of their stroke and the exhaust valve is fully open. When the piston approaches or reaches the upper end of its stroke, the exhaust valve cranks have turned far enough to close the exhaust valve and as this closing movement is effected while the cranks are turning upward through the side portion of their stroke, the valve is closed with a quick movement. This condition is illustrated in Fig. 3, in which view the piston is shown as having started on its downward or outward intake stroke. At this time the intake valve cranks are both turning downward through the side portion of their stroke and therefore open the intake valve with a quick movement. These intake valve cranks are turning through the lower portion of their stroke during the intake movement of the piston and therefore hold the intake valve practically in full open position during the most of this stroke of the piston.

On the compression stroke of the engine, illustrated in Fig. 4, both sets of valve cranks have turned far enough to close both valves and during the power stroke, illustrated in Fig. 5, said valve cranks in their continued turning lift the valves further and therefore further seal them during such power stroke.

At the commencement of the exhaust stroke, indicated in Fig. 6, the exhaust valve cranks are both turning downward through the side portion of their stroke and therefore quickly open the exhaust valve. During this stroke the full time intake valve crank 35 is turning upward through the side portion of its stroke while the half time inlet valve crank 36 is turning downward. The tendency of the slow turning crank 36 to open the intake valve at this time is therefore overcome and compensated for by the more swiftly turning valve crank 35.

45 A similar effect is observable in respect to the exhaust valve during the compression stroke. Here, as shown in Fig. 5, the full time crank 20 is turning in a direction to open the exhaust valve, but at the same time the other crank 21 is turning in a direction to close the exhaust valve. The movement of one is thus compensated for by the movement of the other and the valve is held properly closed during this period.

55 In Fig. 7 I have illustrated how the motor may be constructed with overhead valves. In this view I have illustrated the head portion of the cylinder at 41 and have shown one of the valves at 42, controlling the valve ports 43, said valve being operated by the rocker 44 directly pivoted thereto at 45 and actuated by the two cranks 46 and 47 through the medium of connecting rods 48 and 49. The valve cranks in this case are 60 located over the head of the cylinder.

If desired, the connecting rods between the valve cranks and rockers may be dispensed with by causing the crank pins to operate in the slots or guideways 50 and 51, provided in the opposite ends of the rocker, 70 as indicated in Fig. 8.

From the foregoing it will be seen that by means of this invention a full, clear exhaust and a quick and complete charging of the cylinder may be obtained. The engine 75 is exceptionally quiet in its operation and the eccentric valve operating members disclosed provide a smooth, easy action of the valve parts.

While in the present disclosure I have 80 illustrated practical forms, the invention may take I would have it understood that the structure may be modified in various respects without departure from the true spirit and scope of the invention as defined 85 in the following claims.

What I claim is:

1. An internal combustion engine provided with an intake valve and with a separate exhaust valve, a pair of engine driven 90 cranks, a rigid rocker connected at its opposite ends to said cranks and conjointly operated by said cranks and connected intermediate its ends to the intake valve, a second pair of engine driven cranks and a 95 rigid rocker connected at its opposite ends to said cranks and conjointly operated by said second pair of cranks and connected intermediate its ends to the exhaust valve.

2. An internal combustion engine having 100 a combustion chamber and two piston valve seats each open at one end to the combustion chamber and each provided with a lateral port, a piston valve operating in each seat and having a head traversing the lateral 105 port and exposed at all times to the pressure of the combustion chamber, a pair of engine driven eccentric members, connections from both said members for conjointly operating one of the valves, a second pair of engine 110 driven eccentric members and conjointly operated connections from said second pair of eccentric members for operating the other valve.

3. In an internal combustion engine provided with separate piston valves for the intake and for the exhaust, rigid rockers each connected intermediate its ends with one of said piston valves, a pair of engine driven eccentric operating members connected respectively with opposite ends of the rigid rocker for the intake valve and a pair of engine driven eccentric operating members connected respectively with opposite ends of the rigid rocker for the exhaust valve. 115

4. In an internal combustion engine provided with separate intake and exhaust valves, a pair of engine driven cranks operatively connected with the intake valve and a pair of engine driven cranks operatively 120

connected with the exhaust valve and offset with respect to the first pair of cranks.

5. In an internal combustion engine provided with separate intake and exhaust valves, a pair of engine driven cranks operatively connected with the intake valve and a pair of engine driven cranks operatively

connected with the exhaust valve and offset 180 and 90 degrees with respect to the cranks of the first pair.

10

In witness whereof, I have hereunto set my hand, this 16th day of September, 1919.

HENRY C. STOLL.
